UNITED STATES PATENT OFFICE.

EDWARD D. MURPHY, OF SEATTLE, WASHINGTON.

UNIVERSAL PISTON-RING COMPRESSOR.

Application filed March 8, 1928. Serial No. 260,008.

The invention is a device that may be placed at the end of a cylinder which will compress the rings in a piston as the piston is forced through it into the cylinder.

5 The object of the invention is to provide means for compressing the rings in a piston as the piston is inserted in the cylinder.

Another object of the invention is to provide means for compressing the rings in a 10 piston through which the piston may be forced as it is inserted into the cylinder.

Another object of the invention is to provide means for compressing the rings in the 15 grooves of a piston which may readily be adjusted to fit a piston of any size.

20 A further object of the invention is to provide means for compressing the rings of a piston as the piston is forced through it which does not require that the rings be compressed individually.

A still further object of the invention is to provide a device for compressing rings in pistons which may be stamped from a thin flat piece of material.

25 And a still further object of the invention is to provide a device for compressing piston rings as the piston is inserted in the cylinder which is of a simple and economical construction.

30 With these ends in view the invention embodies a thin piece of material with the edges curved about a center so that when it is rolled it will form a gradually tapering cone. The device is provided with clips and adjustable 35 means for holding it in a circular position.

Other features and advantages of the invention will appear from the following description taken in connection with the drawings wherein:

40 Figure 1 is a cross section through the device and lower end of a cylinder showing the device as it would be used to compress the rings in a piston passing through it into the cylinder.

45 Figure 2 is a view showing the device in the open position or as it would appear when stamped from a flat piece of plate.

Figure 3 is a cross section through the central portion of the device looking downward 50 and showing the adjustable means for holding it at different diameters.

In the drawings the device is shown as it would be made wherein numeral 1 indicates a flat piece of material with the edges 2 and 3 curved as shown or in such a manner that as the device is rolled as shown in Figure 3

it will produce a cone with a gradual taper as shown in Figure 1. Clips 4 are provided at one end of the plate 1 as shown in Figures 1 and 2 which fit over the edge at the open 60 end to hold one end of the device to the other. It will be seen that when assembling the device the end as indicated by the numeral 5 may be rolled and placed through the clips 4 as shown in Figure 1. The end 5 is also provided with clips 6 and 7 which are spot welded or permanently attached in any suitable manner to the outer face of the plate. The clip 6 is provided with an opening 8 through which a bolt 9 is placed having a nut 10 on 65 the inside and being attached to a chain 11 through a loop 12 at the other end. The clip 7 is provided with a notch 13 in which the chain may be held as shown. After the end 5 has been inserted through the clips 4 the 70 chain 11 may be wrapped around the device and inserted in the notch 13 so that it will positively hold the device as shown in Figure 3 and the diameter of the device may 75 readily be changed by removing the chains 80 from the notch 13 and placing one of the other links therein. The holding means may also be adjusted to distances between the length of a link by the bolt 9 as this may be screwed outward or inward to provide adjustment 85

corresponding to the length of the link. It will therefore be observed that the device may be readily adjusted very accurately and to any suitable size. The edge 2 at the lower end of the device is flared outward slightly 90 as indicated by the numeral 14 shown in Figure 1 so that the device will not attempt to enter the cylinder. The thickness of the device is considerably exaggerated for the purpose of illustrating as it is made of very thin 95 material, preferably about ten thousandths of an inch thick. The exact thickness is of course immaterial as material of any suitable thickness may be used.

It will be understood that changes may be 100 made in the construction without departing from the spirit of the invention. One of which changes may be in the exact shape or design of the plate as it is understood the exact curvature or the exact slope of the 105 cone is immaterial, another may be in the use of other means for holding the ends of the plates, and still another may be in the use of other means for providing the adjustment.

110 The construction will readily be understood from the foregoing description. To

use the device it may be made and assembled as shown and described and when it is desired to place a piston in a cylinder the piston is first placed through the device and it is very apparent from Figure 1 that as it is pushed through, the rings will be compressed into the ring grooves and the piston may enter the cylinder with the rings compressed. It is also apparent that this device will facilitate the assembling of pistons into cylinders as the piston may be rapidly forced straight into the cylinder without twisting or working it in so that considerable time will be saved. Figure 1 shows the piston entering the end of the cylinder with the device over the piston and the first ring compressed into place with the second ring slightly compressed and the third ring extending outward and as the movement of the piston into the cylinder is continued the second and third rings will be compressed around the entire piston and as they enter the cylinder the rings will be compressed into the ring grooves. The operation of the device is

therefore very simple and as it may readily be adjusted to pistons of different sizes it will greatly facilitate the assembling of motors.

Having thus fully described the invention, what I claim as new and desire to secure by Letters Patent is:—

1. In a device of the class described, a thin piece of material adaptable to form a cone when rolled, clips at the edges of one end adaptable to slide over the other end as it is rolled, other clips on the outer surface, a screw mounted in one of the clips, and a chain attached to the said screw, the other of the said clips having a notch therein adaptable to engage and hold the chain.

2. In a device of the class described, a thin piece of material having two edges thereof curved in such a manner that as it is rolled it will form a cone with a slight taper, clips at the edges of one end through which the other end slides, and means for holding the said device in different diameters.

EDWARD D. MURPHY.
